COLOR PHOTOGRAPHY STRUCTURE

Rowland S. Potter, Brightford Heights, N. Y., assignor to Defender Photo Supply Company, Incorporated, Rochester, N. Y., a corporation of New York

Application December 10, 1936, Serial No. 115,181

2 Claims. (Cl. 95—2)

This invention relates to a color photography structure, and has to do more particularly with a film pack or plate of the type that includes a series of light sensitive or emulsion layers which 5 are responsive to different colors and are held in superposed relationship one upon the other during exposure, either with or without filtering layers interposed between the light sensitive layers.

10 A principal object of the invention is to afford a photographic film pack or plate in which the light sensitive layers are held together closely without any air space between them during exposure so that sharp and distinct definition of 15 the subject on the negatives is obtained, and which permits ready separation of the light sensitive layers after exposure so that prints can be made from the several negatives independently of each other.

20 In a more specific aspect, the invention has for its object to provide a photographic film pack or plate for color photography in which the several light sensitive layers are united by an adhesive or cementitious substance spread over the 25 adjacent surfaces of the emulsion or light sensitive layers and acting to hold them in close union during exposure. The adhesive or cementitious substance is of a transparent nature and of such character as to permit pulling apart or otherwise 30 separating the several sensitive layers after exposure, so that they may be printed independently, such separation of the layers being possible without resorting to dark room treatment or delicate handling of the film.

35 To these and other ends, the invention consists in the construction and arrangement that will appear clearly from the following description when read in conjunction with the accompanying drawing, the novel features being pointed out in 40 the claims following the specification.

In the drawing:

Fig. 1 is a sectional view of a photographic film showing one embodiment of the invention, and

45 Fig. 2 is a similar view illustrating a modified arrangement where a filter layer is used.

For a complete understanding of the invention, it will be helpful to have a knowledge of the known types of color photography film. In one form of such film, the several layers sensitive to 50 different colors are held together permanently by cement or natural cohesion and may not be separated. This type of construction is suitable only for transparencies, and does not permit making prints from the negatives.

55 In another type of film, the several emulsion

or light sensitive layers are held superposed one on the other during exposure by mechanical pressure, and without the interposition of any cementing material between the layers. This form of construction is open to the objection that 5 close contact between the light sensitive layers cannot be had and a certain amount of air is pocketed between the adjacent surfaces of the light sensitive layers, resulting in lack of clear definition or distinctness of the subject on the 10 negatives.

In a third type of film, the light sensitive layers are held together during exposure by cement such as certain forms of wax, which can be removed to separate the layers after exposure, and before 15 development. To do this, it is necessary to subject the film to heat, solvents, or both, and these operations must be performed in darkness since the film has not been developed, making the procedure difficult and one which has not gone 20 beyond the experimental stage, or proved commercially successful.

According to my invention, the emulsion or light sensitive layers are held together by means that avoids pocketing air between the adjacent surfaces of the layers, while holding them in close contact, and permitting both exposure and development of the several layers as a unit and ready separation thereof after development for 25 independent printing.

One practical way of accomplishing this consists in the use of a transparent cementitious or adhesive substance such for example as a water solution of soap which is liquid-permeable to allow penetration of the developing liquids to the several layers and which adheres less tightly than 30 gelatin layers adhere to each other, in order to permit subsequent separation of the layers, as will be described in more detail later.

It has been found that a one per cent solution of soap and distilled water is satisfactory for the purpose, the solution being spread on the layers rather thinly but in such amount that it will retain the surfaces intimately in engagement, although the invention is not confined to the use 40 of a soap solution as I may employ any other available substances that possess the necessary characteristics as herein outlined.

In the drawing, referring to Fig. 1, 1 designates a support or base which can be of cellulose nitrate or cellulose acetate, while 2 indicates a 50 gelatin or colloidal backing conventionally used to retain the film in a flat state. 3, 4 and 5 designate the emulsion or light sensitive layers, respectively sensitive to the primary colors.

The light sensitive layer 3 adjacent to the base 1 is permanently attached thereto, while 6 designate films or layers of cementitious or adhesive substance such as soap arranged between layers 3 and 4 and between layers 4 and 5. Thus the several layers are held on the base 1 as a unit and the space between the layers is free of air and completely filled with the adhesive. It will be understood that the base 1 may be constructed 10 of glass instead of the material of which the usual film base is made, also that one or more filter layers may be employed if desired.

In Fig. 2, a structure is illustrated embodying a base 7, gelatin backing 8, emulsion or light 15 sensitive layers 9, 10 and 11, and adhesive or cementitious substance 12. 13 designates a filtering layer which may be arranged between the emulsion layers 9 and 10 and permanently attached to the latter, acting to permit only red 20 and green light to come through to the light sensitive layers 10 and 11, the first layer 9 nearest the lens being sensitive only to blue light. The third light sensitive layer 11 may be sensitive to red and blue only, where this arrangement 25 is employed, or if desirable, a red filtering layer may be interposed between the light sensitive layers 10 and 11.

The use of such filter layers is no different from the known practice in the manufacture of 30 color photography film, and where a filter layer is employed, as in Fig. 2, the cementitious or adhesive substance 12 may be interposed between the outer light sensitive layer 9 and the adjacent filter layer 13, the latter being permanently secured to the inner light sensitive layer 10, and the use of the gelatin backing, designated at 2 in Fig. 1 and 8 in Fig. 2, is in 35 accord with conventional practice and may be omitted, if preferred.

Such a film or plate can be exposed in the usual manner, and subsequently developed as a unit, the cementitious or adhesive substance such as soap being transparent and liquid-permeable so that the structure may be subjected 40 to the usual photographic developing solutions which will penetrate all parts of the several light sensitive layers.

After completion of the developing operation, the two outer light sensitive layers can be removed from the remaining layer which is left 45 permanently attached to the base so that the three negatives can be separated for independent printing operations. This separation of the layers can be effected in any convenient way, as for instance by the conventional stripping method, in which the entire unit is first dried, and then pressed by a squeegee or other operation 50 against a separate film base coated with a dry gelatin layer, the latter being immersed in a weak solution of gelatin or water just prior to the stripping operation.

The outer layer 5 or 9 of the film structure is pressed against the separate film base referred to and allowed to dry, after which the outer 55 layer will have adhered to the separate film base to a greater degree than the soap attached surfaces adhere to each other. The separate film base can be stripped or pulled away and carries with it permanently attached thereto the outer

layer 5 or 9, constituting then an individual negative which can be printed independently of the others.

By the same procedure, another separate dry 5 gelatin coated base is dipped in a weak solution of gelatin or water, and the remaining film unit pressed thereagainst, causing adherence of the second layer 4 or 10, which can be pulled away from the third or remaining layer of the film structure and is permanently attached to 10 its separate film base. The third layer 3 or 11 remains attached to its base of the original film structure, and the three sensitized layers or negatives are then available for separate printing 15 operations.

The character of the adhesive or cementitious substance is such as to permit ready separation of the several layers when subjected to a stripping operation such as described above, but it will be understood that other methods of separation than that described may be employed, and the essential feature of the invention embodied herein depends upon the use of means such as a suitable adhesive that will hold the light sensitive layers together with sufficient permanence and being of such a nature as to permit their exposure and development as a single unit, while enabling their subsequent separation to 20 permit independent printing operations. Where "soap" or "soap solution" is mentioned throughout the specification and claims, it is intended to mean or comprehend any water soluble alkali salt of the acids which occur in fats or oils.

While the invention has been described with reference to certain structural embodiments, it 25 is not confined to the precise disclosures herein, and this application is intended to cover any modifications or departures coming within the contemplation of the improvements or the scope 30 of the following claims.

I claim:

1. A color photography structure comprising a plurality of layers of material sensitive to different colors, the layers being held together and separated only by an extremely thin stripping 45 layer consisting of a transparent liquid-permeable adhesive comprising a soap solution which fills the space and excludes any air between the layers, holding said sensitive layers in optical contact and permitting their development while 50 secured together and subsequent separation for printing independently of each other.

2. A color photography structure comprising a base and a plurality of layers of material sensitive to different colors, one of said layers being permanently secured to the base and the remaining layers being secured to the first layer and to each other by an extremely thin stripping 55 layer consisting of a transparent liquid-permeable adhesive comprising a soap solution that fills the space and excludes any air between the layers and between said base and the adjacent layer, said liquid-permeable adhesive acting to hold said sensitive layers in optical contact and to permit development of the different layers 60 while secured together and separation of the layers after development for printing independently of each other.

ROWLAND S. POTTER.
